(57) **CLAIM**

The ornamental design for a conduit coupler, as shown and described.

DESCRIPTION

FIG. 1 is a perspective view of a conduit coupler showing the new design;

FIG. 2 is a first side view thereof with a nut attached;

FIG. 3 is a second side view thereof with the nut attached, the second side view opposite the first side view;

FIG. 4 is a top view thereof;

FIG. 5 is a bottom view thereof;

FIG. 6 is the first side view as shown in FIG. 2 with the nut removed; and,

FIG. 7 is a perspective view showing the conduit coupler in a position of use in an example environment.

The broken lines shown in the drawings represent portions of the conduit coupler and environment that form no part of the claim.
